US00D972357S

(12) **United States Design Patent** (10) Patent No.: **US D972,357 S**
(45) Date of Patent: **** Dec. 13, 2022**

(54) **KETTLE**

(71) Applicant: **MIDEA GROUP CO., LTD.**,
Guangdong (CN)

(72) Inventor: **Wenquan Lu**, Guangdong (CN)

(73) Assignee: **MIDEA GROUP CO., LTD.**, Foshan
(CN)

(**) Term: **15 Years**

(21) Appl. No.: **35/511,358**

(22) Filed: **Nov. 6, 2020**

(80) **Hague Agreement Data**

Int. Filing Date: **Nov. 6, 2020**

Int. Reg. No.: **DM/212517**

Int. Reg. Date: **Nov. 6, 2020**

Int. Reg. Pub. Date: **Feb. 12, 2021**

(30) **Foreign Application Priority Data**

Aug. 20, 2020 (CN) 202030478676.8

(51) **LOC (13) Cl.** **07-01**

(52) **U.S. Cl.**

USPC **D7/318**

(58) **Field of Classification Search**

USPC D7/300, 301, 302, 309, 312, 313, 314,
D7/316, 317, 318, 321, 322, 619.1, 622,

D7/354

CPC A47J 27/06; A47J 27/21; A47J 27/21008;
A47J 27/212; A47G 19/12; A47G 19/14;
A47G 19/127

(74) Attorney, Agent, or Firm — Morgan, Lewis & Bockius LLP

(57) **CLAIM**

The ornamental design for a kettle, as shown and described.

DESCRIPTION

1. Kettle

1.1 : Front

1.2 : Back

1.3 : Left

1.4 : Right

1.5 : Top

1.6 : Bottom

1.7 : Perspective

The broken lines depict portions of the kettle that form no part of the claimed design.

1 Claim, 7 Drawing Sheets

US D972,357 S
